UNITED STATES PATENT OFFICE.

CORNELIUS AMBRUSTER AND HAROLD M. BECK, OF CHICAGO, ILLINOIS.

BOOSTER REGULATION.

1,084,595.

Specification of Letters Patent. Patented Jan. 20, 1914.

Application filed March 24, 1903. Serial No. 307,802.

To all whom it may concern:

Be it known that we, CORNELIUS AMBRUSTER and HAROLD M. BECK, both citizens of the United States, and residing at Chicago, in the county of Cook and State of Illinois, have invented certain new and useful Improvements in Booster Regulation, of which the following is a specification.

Objects of the present invention are to 10 effect accurate and proper regulation of a booster for causing it to compel or control the charge or discharge of a battery; to provide simple and comparatively inexpensive and efficient apparatus constituting a booster 15 regulator; and other objects of the invention as well as its characteristic features will appear from the following description taken in connection with the accompanying drawings forming part hereof and in which—
20 Figure 1, is a diagrammatic view illustrating a system of distribution embodying features of the invention, and Figs. 2, 3, 4, 5, 6, 7, 8, 9, 10, 11 and 12, are similar views of systems of distribution embodying modifications, or different applications of the invention.

In the drawings *a*, is a generator arranged to supply current to the consumption circuit 1, 2, on which circuit may be a variable load, 30 as for example, that of the trolley car *b*. *c*, is a storage battery having interposed in series with it and in its conductors 3—4 a booster *d*, which may be driven in any appropriate manner. These described parts, as 35 well as the variety of ways in which they may be operatively connected, are well understood.

There is a make-and-break field regulator responsive to changes of electrical condition 40 in some part of the system. Fluctuations of load on the generator *a*, are an example. This regulator operates to control the voltage of the booster in such a way as to cause it to compel the battery to charge or discharge, the effect being that a comparatively small change, for example, increase of load above the average on the generator produces or tends to produce a magnified effect on the booster which would if continued cause the 50 battery to discharge excessively and not only take the increase of load above the average, but also largely if not wholly relieve the generator of its average load; however, there is a time element involved which though 55 small, is of importance, so that by the time voltage of the booster has been built up suf-

ficiently to cause the battery to discharge slightly in excess of what it should, the make-and-break device in response to a slight reduction of load on the generator, 60 will cease or reverse its action, thus checking any further tendency to cause an increase of battery discharge. A similar action takes place when the load tends to fall off the generator. Thus the make-and-break device would ordinarily be in a state of vibration and there would be upon the generator a number of fluctuations of such minute amount and duration that its resultant load would be substantially constant notwithstanding fluctuations of the load *b*. When the load *b* corresponds with the average load on the generator the make-and-break device might be at rest and the battery neither charging or discharging. 75 Across the gap or gaps of the make-and-break device are shown condensers *S* to suppress the spark.

Referring to Fig. 1, the regulator is shown as a pole changer and comprises a pivotal 80 arm *e*, arranged in the space between contact points 5 and 6, and having a core *e*¹, and an adjustable spring *e*². The contact points 5, and 6, are connected by conductors 7 and 8, for example, with the leads of the 85 circuit 1, 2. The arm *e*, is properly insulated and connected with a conductor 9, 9^a the current in which influences the field 10, of the booster *d*, and this conductor 9^a, is connected with an intermediate point of the 90 battery. Upon conditions of average load the arm *e*, might not make contact with either of the points 5 or 6, and the battery *c*, would neither charge nor discharge. The 95 core *e*¹, is operatively arranged with respect to a coil *e*³, which in its turn is responsive to the electrical condition of the circuit. Upon an increase of load the coil *e*³, attracts its core *e*¹, and brings the pivotal arm *e*, into contact with the point 6, thus there is a circuit from the battery which may be described as in the direction 9^a, 10, 9, *e*, 6, and 8, to lead 2. The effect of this current is to build up the voltage of the booster *d*, of a polarity to cause the battery to discharge 100 and relieve the generator of the increase of load so as to keep the load on the generator constant. In fact, the circuit thus established tends to cause a maximum discharge of the battery but time is required to build up the voltage of the booster, so that by the time the load on the generator is sufficiently 105 110 115

relieved, the reduction of current in the coil e^3 permits the latter to diminish its pull upon the core e^1 , and thus the arm e , is shifted out of contact with the point 6, and 5 it may even be brought into contact with the point 5. Under the latter condition a circuit is established from conductor 1 by way of 7, 5, e , 9, 10 and 9^a to the middle point of the battery. The current in the 10 last mentioned circuit operates to build up the voltage of the booster e , of a polarity to cause the battery to charge; but as soon as this result begins to take place the effect is to cause the coil e^3 , to bring the arm e , again 15 into contact with the point 6, thus the arm e , may continue to vibrate between these points and the load on the generator a will fluctuate momentarily within such extremely narrow limits that the fluctuations may be disregarded in their effects on the generator. 20 Yet the magnified effects of these fluctuations though overlapping and partly neutralizing each other, will in the aggregate cause the battery to compensate for the fluctuations of the load b .

Referring to Figs. 2, f , f^1 , f^2 and f^3 , represent the arms of a Wheatstone bridge arranged across the circuit 1, 2. The field coil 10 which influences the booster d , is connected across this Wheatstone bridge, between the junction points p and q . The resistance f^3 is greater than that required to produce equal potentials at p and q , so that when it is in the circuit, current tends to 30 flow from the point q , through the conductor 12 and field 10 to the point p , and when all or a sufficient part of the resistance f^3 , is short circuited the current through the field 10, is in the opposite direction. One 35 end of the resistance f^3 is connected with the arm e , and the other end or some point including an appropriate portion of it, is connected with the contact point 13, the hand switch 14 serving to adjust this connection 40 when required. In use the result of the operation of this device is as has been described with reference to Fig. 1. The coil e^3 , serving to bring the arm into and permit it to get out of contact with the contact point 13, 45 whereby the resistance of the arm f^3 , is varied so as to effect reversals in the field controlling coil 10, which influences the voltage of the booster and the operation of the system as has been described. In the arrangement shown in this and in some of the succeeding figures the make-and-break device has but one contact point, whereas in Fig. 1, there are two. Furthermore in the arrangement of Fig. 2, the circuit of the 50 field coil itself is not actually made and broken.

In Fig. 3, there is a conductor 15 from an intermediate point of the battery e , through the field coil 10, thence branching through a 55 resistance f^4 , by conductor 17, to one end of

the battery and through an adjustable resistance 18 by a conductor 19, to the other end of the battery. 20, is a conductor from one end of the resistance 18, to the arm e , and from the contact point 21, leads a conductor 22, to the other end of the resistance 18, or to an appropriate point in it according to the position of the adjusting switch 23.

The result of the operation of the modification illustrated in Fig. 3, is substantially as has been described in connection with Figs. 1 and 2. When the resistance 18, is in circuit, current passes by 17, f^4 , 15 through the coil 10, to the middle point of the battery. When appropriate part of the resistance 18 is short circuited by way of the conductor 20, arm e , contact 21 and conductor 22, there is a current from the middle point of the battery through 10, via conductor 15, through the short circuit at contact point 21, to the battery terminal conductor 3, so that the current through the field 10 is reversed.

Referring to Fig. 4, there is a coil 24, which tends to influence the booster so as to charge the battery and it is shown in that figure as arranged across the circuit 1, 2, but it may be arranged across any appropriate source. There is also a coil 25, responsive to the load on the work circuit and shown as a series coil in the conductor 1. 26, is a resistance in shunt relation to the coil 25. The coil 25, constitutes a field influencing coil for the booster and its tendency is to overpower the coil 24, and influence the booster in such a way as to discharge the battery. The contact point 27, is connected by a conductor 28, with one end of the shunt resistance 26, and the arm e , is connected by a conductor 29, with the other end of the resistance 26, or with an intermediate point in said resistance determined by the position of the adjusting switch 30. When the circuit 28-29, is closed through the contact point 27, the coil 26, or an appropriate part thereof is short-circuited and the coil 24, predominates influencing the booster in the direction to cause the battery to charge. However, when the circuit 28-29 is open at the contact point 27, the coil 25, is energized, preponderates over the coil 24 and influences the booster field in the direction to make the battery discharge. By the means shown in Fig. 4, and described, similar results are effected as are effected in connection with the figures previously described.

As shown in Fig. 5, there is a coil 31 which influences the field of the booster and it is arranged in series with the resistance 32, as shown across the circuit 1, 2, and in a conductor 33 and 34. 35, is a booster field influencing coil responsive to the load b , on the work circuit and shown as a series coil in the conductor 1. The coil 35, tends to

the load b . When this load is less than normal the tendency is for less current to pass through the coil e^3 of the regulator, allowing the pivotal arm e , to contact with the point 5 64 thereby short circuiting the resistance 63 of the field influencing coil 62 of the booster through the conductors x^{11} and x^{12} thereby strengthening the effect of the field influencing coil 62 to increase the voltage of the 10 booster and cause the battery to charge. When the load b , is greater than normal there is a tendency for more than the normal current to flow through the coil e^3 , which causes the arm e to lose contact with the 15 point 64 throwing the resistance 63 in series with the field influencing coil 62 of the booster, reducing its voltage and causing it to send less current to the battery. The coil 62 and the resistance 63 may be connected 20 in series with each other across any convenient source. As shown they are connected by the conductor x^{12} across the circuit of the generator terminals.

The arrangement illustrated in Fig. 11, is 25 one in which the normal voltage of the battery c , may be less than the voltage of the generator a , which is the reverse of the conditions described in Fig. 10, so that in Fig. 11, the voltage of the booster supplements 30 that of the battery and opposes the voltage of the generator so as to insure the proper operation of the battery. The booster field influencing coil 65 and its resistance 66, are arranged as in Fig. 10, as are also the other 35 parts and circuits with the exception that the arm e , is arranged to contact with a point 67 in accordance with the pull of the coil e^3 and short circuit the resistance 66. The absorption of energy by d , may be 40 turned to the line by generator m .

Since the invention is not confined to the use of a coil responding to changes of current, there is shown in Fig. 12, a voltage coil e^6 arranged across some portion of the 45 system, at which voltage changes (minimized by the operation of the battery) occur and in accordance with which changes it is desired to make the battery charge or discharge. In Fig. 12, X and Y , are such 50 points and the voltage changes may occur at them by reason of their distance from the generator or by reason of the characteristics of the generator, or in any other way. The coil e^6 is shown as connected across the 55 points X and Y by a conductor Z . The booster field regulator coil 10, is connected in conductors 68 and 69, which extend from an intermediate point of the battery to the arm e . The opposite ends of the battery 60 are connected respectively by conductors 100 and 101 with the contact points 70 and 71. When the coil e^6 is energized in response to 65 an increase of voltage across the points X and Y , the arm e , is brought into contact with the point 71, producing a current by

way of 68, 69, e , 71, 101 in the coil 10 in such a direction as to cause the booster d , to charge the battery. Likewise if there is a decrease in the voltage across the points X and Y , the coil e^6 allows the arm e , to contact with the point 70 producing a current by the path 100, 70, e , 69, and 68 through the coil 10 in such a direction as to cause the booster to make a battery discharge. 70

We do not regard our invention as limited to the exact details of construction or arrangement, or any of them, and it will appear from our claims that the invention is not so limited, but 75

Having thus described the nature and objects of our invention, what we claim as new and desire to secure by Letters Patent is—

1. The combination with a generator and its complemental storage battery and booster for regulating fluctuations, of means responsive to the fluctuations for furnishing the booster with both positive and negative excitation in excess of the requirements of the fluctuations to be regulated and for both applying impulses of the excessive excitation in appropriate direction and controlling the duration and rapidity of the impulses thereby producing a resultant excitation proportionate to the fluctuations. 80

2. The combination with a generator and its complemental storage battery and booster for regulating fluctuations, of means responsive to the fluctuations for furnishing the booster with both positive and negative excitation in excess of the requirements of the fluctuations to be regulated, said means including a make-and-break device for both applying impulses of the excessive excitation in appropriate direction and for controlling the duration and rapidity of the impulses, thereby producing a resultant excitation proportionate to the fluctuations. 85

3. In combination, in a voltage regulating apparatus, an armature, a field coil for controlling the voltage developed therein, and a make-and-break device adapted to apply to said coil impulses of electro-motive-force alternating in polarity and in rapid succession, whereby each impulse is only 90 partially effective in modifying the armature voltage. 100

4. In an electric regulator the combination of a regulating armature, a coil for controlling its voltage and means for continually applying to said coil electro-motive-forces of alternating polarity, substantially 105 as described. 110

5. In an electric regulator the combination of a voltage regulating armature, a field coil for controlling its voltage, and means for continually applying to said field coil electro-motive forces of fixed amounts, and of alternating polarity, substantially as 115 described. 120

125

130

influence the booster to discharge the battery and the coil 31 tends to influence the booster to charge the battery. The coil 31, preponderates when the resistance 32, is 5 short circuited, otherwise the coil 35, preponderates so that by short circuiting the resistance 32, the results of operation herein described in connection with the other figures can be accomplished. 36, is a conductor leading from one end of the resistance 32, to the arm *e*. From the contact point 37, another conductor 38, leads to the end of the resistance 32, or to an intermediate point in said resistance according to 10 the position of the adjusting switch 39.

In Fig. 6, there are two coils 11 and 16, each of which influences the booster voltage. The coil 16 when energized effects discharge of the battery and the coil 11 when energized effects charging of the battery. These coils are excited from any convenient source and as shown are connected in branches *x* and *y* to a conductor *z*, across the lead 1, 2, the coil 11 having in series 25 with it a resistance 40 and the coil 16 having in series with it a resistance 41. The conductor 45 connects one end of each resistance with the pivotal arm *e*, of the booster regulator. The other ends of the 30 resistances are connected with the contact points 42 and 43 respectively by conductors 44 and 46. Under conditions of average load the pivotal arm *e*, may remain clear of the contact points 42 and 43 and appropriate 35 adjustments made for the booster for this condition. When the coil *e*³ brings the arm *e* into contact with the point 43, resistance 41 is short circuited by way of the conductors 45 and 46, so that the coil 16 predominates. When the arm *e* is in contact with 40 the point 42, the resistance 40 is short circuited by way of the circuit 44—45 and the coil 11 preponderates.

The modification of the invention illustrated in Fig. 7, is very similar to that illustrated and described in connection with Fig. 2. However, in that figure the Wheatstone bridge is normally unbalanced, whereas in Fig. 7, it is balanced. The relative resistances of the branches *f*⁴, *f*⁵, *f*⁶ and *f*⁷ being so determined as to produce the desired condition or potential across the points *p* and *q* of the Wheatstone bridge, across which points the field influencing coil 10 of the booster *d* is connected. The point *q* is connected to the pivotal arm *e* of the booster regulator whose contact points 47 and 48 are connected respectively by conductors 49 and 50 in such a way that when the coil *e*³ causes 55 the arm *e* to contact with the point 48, the resistance *f*⁷ is short circuited unbalancing the Wheatstone bridge and causing a current to flow from the point *p*, through the coil 10 to the point *q* exciting the booster in such a 60 way as to cause the battery to discharge.

Likewise if the arm *e* contacts with the point 47, the resistance arm *f*⁴ is short circuited through the conductor 49 and the Wheatstone bridge is again unbalanced, causing current to flow through the coil 10 in the opposite direction to cause the battery to charge.

Fig. 8, is a modification of Fig. 7, differing from it principally in that an increased change of voltage of the booster is produced for each vibration or movement of the pivotal arm. In Fig. 8, the Wheatstone bridge connection is the same as has been described in Fig. 7, and the same reference letters are therefore employed to denote its branches. The pivotal arm *e*, carries two contacting members *e*⁷ and *e*⁸ insulated from each other. When the coil *e*³ causes the arm *e* to be drawn down the contact piece *e*⁸, short circuits the arm *f*⁷ of the Wheatstone bridge across the contact points 57 and 58 by way of wires *x*¹, *x*², *x*³ and *x*⁴. At the same time the contact piece *e*⁷ short circuits the branch *f*⁶ of the Wheatstone bridge across the contact points 55 and 56 by way of *x*⁵, *x*⁶, *x*⁷ and *x*⁸, the effect of the unbalancing of the Wheatstone bridge being magnified by the short circuiting of two opposite arms instead of one arm as in the case of Fig. 7. Likewise when the pivotal arm *e*, rises, the contact piece *e*⁸ short circuits the branch *f*⁴ of the Wheatstone bridge across the contacts 53 and 54 by way of the conductors *x*¹, *x*⁶ and *x*⁵. At the same time the contact piece *e*⁷, short circuits the branch *f*⁵ of the Wheatstone bridge across the contact points 51 and 52 by way of the conductors *x*³, *x*⁴, *x*⁹, *x*¹⁰, *x*⁸.

The arrangement shown in Fig. 9, is much like the arrangement shown in Fig. 1, differing only in the location and arrangement of the coils which influence the core *e*¹. In the arrangement of this figure the solenoid core *e*¹, is influenced by two coils, one of which *e*⁵ responds to variations of the load *b*, the other coil *e*⁴, is wound in such a way as to oppose the effect of the coil *e*⁵ and its strength is responsive to fluctuations in the battery branch 3—4. The combined effect of the two coils *e*⁴ and *e*⁵ is the same as the effect of the coil *e*³ in Fig. 1.

In the arrangement shown in Fig. 10, the load *b*, is connected directly across the battery terminals and an additional load *L*, preferably of a non-fluctuating character may be connected across the terminals of the generator *a*. In the arrangement shown the battery may be of a higher voltage than that of the generator *a*. The booster *d*, normally generates an amount of voltage equal to the difference between that of the battery and that of the generator *a*. Under these conditions it is unnecessary to reverse the polarity of the booster *d*, the booster regulator operating to make the voltage of the booster *d*, greater or less according to fluctuations of

6. In an electric regulator a regulating armature, a coil for controlling its voltage and means for continually applying to said coil electro-motive-forces of fixed amounts and of alternating polarity, substantially as described.

7. In an electric regulator the combination of a regulating armature, a field coil for controlling the voltage of said armature and
10 means including a make-and-break device for continually applying to said field coil

electro-motive-forces of fixed amounts, and of alternating polarity, substantially as described.

In testimony whereof we have hereunto 15 signed our names.

CORNELIUS AMBRUSTER.
HAROLD M. BECK.
